WRIST PACT

Filed July 3, 1928

Inventor
Albert Hagel
Seymour Earle Nichols
Atty.

UNITED STATES PATENT OFFICE.

ALBERT HAGEL, OF NEWARK, NEW JERSEY, ASSIGNOR TO CHASE COMPANIES INC., OF WATERBURY, CONNECTICUT, A CORPORATION.

WRIST PACT.

Application filed July 3, 1928. Serial No. 290,129.

My invention relates to an improved wrist pact, as vanity cases designed to be worn on the wrist are sometimes called, the object being to produce a device of the character described at a low cost for manufacture, of superior simplicity, convenience and appearance.

With these ends in view, my invention consists in a wrist pact having certain details of construction and combinations of parts as will be hereinafter described and particularly pointed out in the claims.

In the accompanying drawings:

Fig. 1 is a plan view of my improved wrist pact;

Fig. 2 is a view thereof in side elevation;

Fig. 3 is an enlarged plan view thereof with its cover open and in the vertical position;

Fig. 4 is an enlarged sectional view on the line 4—4 of Fig. 1;

Fig. 5 is a detached perspective view of the case-body; and

Fig. 6 is a detached view of one of the two ribbon-loops.

In carrying out my invention as herein shown, I employ an oblong case-body 10 having four corresponding beveled corners 11 formed near their lower edges with perforations 12 for the reception of the pintles 13 of two one-piece wire-loops 14 having centrally-arranged outwardly-projecting offsets 15 for the reception of the ribbons or straps which pass around the wrist of the wearer of the pact. Within the said case-body I locate a bottomless oblong case-lining 16 just enough shorter and narrower than the case-body to fit snugly within the same but wider than the same is deep, so as to project above the upper edge thereof, as shown in Fig. 4, to form a guard-flange 17. The four corners of the said case-lining are correspondingly concaved at 18 so as to form clearance-spaces 19 within the case-body for the reception and play of the pintles 13 of the wire-loops 14, whereby also the powder contained within the case-lining is prevented from working through the perforations 12 made in the beveled corners 11 of the case-body for the reception and play of

the pintles 13, as clearly shown in Fig. 3. The cover 20 of the pact is secured thereto by a hinge 21 and shuts over the projecting upper edge or flange 17 of the case-lining 16, thus forming a tight joint between the case-body and the cover. As shown, the cover is formed with a flat top 22, edge bevels 23 and corner bevels 24, but the design of the cover may be varied as desired. As shown, the cover is locked in its closed position by a snap-spring 25 secured to the inner face of one end of the case-lining 16 and having a lug 26 projecting above the upper edge thereof and provided with a projection 27 snapping into a slot 28 in one end of the cover.

I claim:

1. A wrist pact having a case-body provided with four beveled corners each having a perforation, two pivotal wire loops having pintles entering the said perforations, and a case-lining fitted within the said case-body and having its four corners inset to clear the said pintles and form clearance-spaces for the same.

2. A wrist pact having a case-body formed with four beveled corners each having a perforation, two pivotal wire loops having pintles entering the said perforations, a case-lining fitted within the said case, projecting above the upper edge thereof and having its four corners inset to provide clearance-spaces for the loops, and a cover hinged to the said body and fitting over the projecting upper edge of the said case-lining.

3. A wrist pact having a case-body formed with four beveled corners each having a perforation, two pivotal wire-loops having pintles entering the said perforations, a case-lining fitted within the said case-body, having its four corners concaved to clear the said pintles and form clearance-spaces therefor and adapted to project above the upper edge of the case-body, a cover hinged to the said body, and locking means for the cover.

In testimony whereof, I have signed this specification.

ALBERT HAGEL.
